Owens-Corning Fiberglas Corporation, a corpora-
tion of Delaware

Filed July 31, 1968, Ser. No. 12,972

Term of patent 14 years

Int. Cl. D5—09

U.S. Cl. D87—3

The figure is a plan view of an embossed plastic sheet material showing my new design. A design unit is contained within the rectangle shown. The design is repeated over the film in an offset relation as shown by the extensions beyond the border of the rectangle.

I claim:

The ornamental design for an embossed plastic sheet material or similar article, substantially as shown and described.
